UNITED STATES PATENT OFFICE.

EMANUEL B. CASE, OF MOUNT VERNON, MISSOURI.

FEED-CHOPPING APPARATUS.

SPECIFICATION forming part of Letters Patent No. 552,820, dated January 7, 1896.

Application filed September 11, 1895. Serial No. 562,196. (No model.)

To all whom it may concern:

Be it known that I, EMANUEL B. CASE, a citizen of the United States, and a resident of Mount Vernon, in the county of Lawrence and State of Missouri, have invented certain new and useful Improvements in Feed-Chopping Apparatus; and I do hereby declare that the following is a full, clear, and exact description of the invention, which will enable others skilled in the art to which it appertains to make and use the same, reference being had to the accompanying drawings, which form a part of this specification.

My invention relates to apparatus for grinding or chopping wheat, corn, and other like substances for feeding to stock, and its object is to provide an improved construction of same which will possess superior advantages with respect to efficiency in use.

The invention consists in the novel construction and combination of parts hereinafter fully described and claimed.

In the accompanying drawings, Figure 1 is a longitudinal sectional view of a feed grinding or chopping apparatus constructed in accordance with my invention. Fig. 2 is a plan view of the same.

In the said drawings, the reference-numeral 1 designates four uprights connected together by end bars 2 and side bars 3, forming a rectangular frame.

The numeral 5 designates a series of intermediate bars parallel with the bars 3.

Journalized in bearings on one of the side bars 3 and one of the bars 5 is a shaft 6, provided with a bur 7, having a series of peripheral corrugations or beveled ribs 8 at equal distances apart and extending from end to end of the bur. The bur is also provided with heads 9. The shaft at one end is provided with a cog-wheel 10, with which meshes a larger cog-wheel 12 on a shaft 13, provided with a crank 14. Meshing with the cog-wheel 12 is a similar wheel 15 on a shaft 16, provided with a crank 17. This latter wheel and shaft are for furnishing additional power to turn the bur and may be dispensed with, if desired. At the opposite end shaft 6 is provided with a fly-wheel 18 and also with a pulley 19, which may be connected with any

suitable motor for driving the apparatus by power.

Secured to the bars 3 at one side of the apparatus and to the top and bottom bars 5 are two horizontal aligned boards 20, each provided with a rectangular aperture 21. These boards are secured in place by means of bolts 23, which pass through slots in the ends of the boards. These boards are held in place by means of nuts 24, provided with finger-holds 25.

The numeral 26 designates a vertical stationary bur concaved on its inner side and formed with a number of corrugations or ribs, the distance between which gradually decreases from top to bottom. The said corrugations or ribs are inclined on their lower sides and straight on their uppersides, forming cutting-edges. This bur has its upper and lower ends cut away, forming lugs 20^a, which fit in the rectangular apertures in the boards 20, and interposed between the said bur and the outer end of the apertures are rubber or other elastic cushions or springs 20^b, which allow the bur to yield slightly, so as to avoid injury to the apparatus should it become clogged.

Secured to the bars 2 at one end of the apparatus are cam-levers 27, which are adapted to engage with the boards 20, so as to adjust the latter and regulate the distance between the burs.

A drawer 28 is located at the lower part of the apparatus to receive the ground or chopped grain as it comes from the burs, and at the upper end the stationary bur is formed with side walls 29 and a front wall 30, forming a hopper to direct the grain to the burs.

The operation will be readily understood. The set-nuts are loosened and the cam-levers operated so as to adjust the stationary bur, when the nuts are tightened to hold the bur and its boards in place. The rotating bur is now operated either by hand or power and the grain to be chopped or ground introduced into the hopper, from whence it will fall on the rotating bur and be carried between it and the stationary bur and ground or chopped by the beveled ribs or corrugations.

An apparatus constructed as above will be

very efficient in use and will occupy but little space, and being of but little weight can be readily transported from place to place.

Having thus fully described my invention,
5 what I claim is—

1. In a feed grinding or chopping apparatus, the combination with the frame, and the rotatable bur having beveled corrugations or ribs, of the horizontally adjustable boards 10 having slots therein, the screw bolts passing therethrough and the finger nuts, the vertical bur concaved on its inner side and provided with corrugations or ribs at varying distances apart, said bur cut away at the ends forming 15 lugs engaging with apertures in said boards, and formed or provided at its upper end with a hopper, substantially as described.
2. In a feed grinding or chopping apparatus, the combination with the frame, the rotatable 20 bur having beveled corrugations or ribs and

a head at each end and means for rotating said bur, of the horizontally adjustable boards formed with slots near each end and with rectangular apertures, the screw bolts passing through said slots, and the finger nuts, the vertical bur having lugs at the ends engaging with apertures in said boards, having its inner side concaved and formed with corrugations or ribs at varying distances apart, the 25 springs interposed between said bur and the walls of the rectangular apertures therein, and the hopper, substantially as described.

In testimony that I claim the foregoing as my own I have hereunto affixed my signature in presence of two witnesses.

EMANUEL B. CASE.
